UNITED STATES PATENT OFFICE

2,342,897

ELECTRON DISCHARGE DEVICE SYSTEM

Hallan Eugene Goldstine, Port Jefferson, N. Y., assignor to Radio Corporation of America, a corporation of Delaware

Original application August 10, 1939, Serial No. 289,337, now Patent No. 2,252,370, dated August 12, 1941. Divided and this application July 1, 1941, Serial No. 400,578

8 Claims. (Cl. 250—36)

This invention is a division of my application Serial No. 289,337, filed August 10, 1939, now United States Patent 2,252,370, granted August 12, 1941.

The invention relates to ultra high frequency electron discharge device systems. In particular, the invention relates to an ultra high frequency oscillation generation system and to an efficient mechanical construction for the same.

One of the objects of the present invention is to provide a construction for an ultra high frequency oscillator system which is suitable for use on frequencies of the order of 500 megacycles, wherein one or several vacuum tubes may be employed depending on the power output desired.

Another object is to provide a novel mechanical construction for an ultra high frequency system which minimizes the inductance of the connections to the vacuum tube electrodes.

Another object of the present invention is to provide a highly efficient ultra short wave generator circuit employing a vacuum tube having a plurality of leads for each of the grid and anode electrodes.

Another object is to provide means for making most effective use of vacuum tubes in which a plurality of leads are provided for each of the electrodes which carry radio frequency currents.

Although the present invention is hereinafter described in connection with electron discharge devices of the triode type whose grid and anode electrodes each have a pair of terminal connections or leads extending from opposite sides of the envelope, it should be distinctly understood that the invention is not limited to the use merely of a pair of such leads for each electrode since obviously more than two leads can be used for each of the electrodes.

A feature of the invention relates to the mechanical constructions for deriving output power, and to the arrangements for grouping a plurality of the vacuum tubes in parallel with a minimum of inductance in the electrode connections.

The novel constructional arrangement of the invention as herein described has been successfully used in generating power at 500 megacycles, although it will be understood that the various elements thereof as well as the circuit as a whole may be used in other circuit schemes.

In one embodiment of the invention there are employed a plurality of electron discharge devices of the vacuum tube type wherein the grid and anode of each device are each provided with a plurality of terminal connections and there is coupled to these terminal connections a low loss

tank circuit. Tuning means are provided in the filament circuits of the vacuum tubes.

The following is a detailed description of the invention in conjunction with drawings, wherein the same reference numerals are used throughout the figures to designate the same parts.

Fig. 1 is a schematic circuit diagram of an ultra high frequency oscillator system in accordance with one embodiment of the invention employing a single resonant concentric line to control the frequencies of a plurality of vacuum tubes in electrically parallel relation, and another resonant concentric line in common with the filaments of these parallel connected tubes;

Fig. 2 is a front elevation of the complete mechanical construction employed for the oscillator system of Fig. 1;

Fig. 3 is a rear elevation of any quarter of the mechanical construction of Fig. 2, it being understood that all quarters are alike;

Fig. 4 is a section of Fig. 2 along the line 4—4;

Fig. 5 is a perspective view of a filament coupling loop employed for each vacuum tube in the system of Figs. 1 and 2;

Fig. 6 is a section of a unit employed in the mechanical construction for accommodating the grid choke coil and anode sleeve connection for each vacuum tube oscillator;

Fig. 7 is a schematic circuit diagram of another embodiment of the invention employing individual concentric lines for tuning the filaments of the vacuum tube oscillators;

Fig. 8 is a front elevation of any quarter of the complete mechanical construction for the circuit of Fig. 7, it being understood that all quarters are alike;

Fig. 9 is a rear elevation of any quarter of the complete mechanical construction for the circuit of Fig. 7;

Fig. 10 is a fragmentary side view of the mechanical construction for Fig. 7, showing in section details of one of the individual filament concentric lines. In effect, Fig. 10 shows half of the construction of Fig. 4, modified to omit the common outer concentric line and to include the individual concentric line; and

Fig. 11 is a section of one of the filament concentric lines of the circuit of Fig. 7.

Referring to Fig. 1 in more detail, there is shown a low loss, resonant concentric line comprising an inner conductor 1 and an outer conductor 2, to the inner conductor of which are inductively coupled through coils 3, 3 four individual short wave oscillation generator vacuum tubes 4, 4. The resonant concentric line 1, 2

is generally of the type described in the article by Clarence W. Hansell, published in the A. I. E. E., Transactions of August, 1935, pages 852 to 857. Each vacuum tube oscillator comprises an anode 5, a control electrode or grid 6, and a filament 7, to the grid of which is connected a tuned U-shaped loop, herein designated schematically as 8. The terminals for the anode and grid electrodes of each of these vacuum tubes extend from these electrodes through opposite sides of the envelope, so as to minimize lead connections, while the filament leads of each vacuum tube extend through one end of the envelope. The general configuration of these vacuum tubes 4, 4 are shown in more detail in Fig. 2, which will be described later. The grid circuits of the vacuum tubes are by-passed to ground by capacitors 8, 8 and supplied with suitable negative direct current bias through choke coils 9, 9 which, taken together with capacitors 10, 10 form filters for preventing radio frequency fluctuations on the grids from entering the direct current power supply. The anodes of the vacuum tubes are grounded for radio frequency energy by means of by-pass capacitors 11, 11. The filaments of the vacuum tubes are all coupled in common through loops 12, 12 to a single concentric line formed from the outer surface of conductor 2 and a surrounding cylindrical conductor 13. The active parts of the filaments are maintained at a radio frequency potential and this potential is determined by means of tuning the filament reactance. The center of each filament is coupled to ground through a capacitor 16 which serves to tune out the reactance of the filament leads. The outer legs of each filament are by-passed to the loop 12 and thence to ground, while heating energy for the filament is obtained from leads 17 which extend through the loop 12, as shown. In this way the filament of each tube floats above ground potential. From what has been stated above, it will be apparent that the low loss resonant line 1, 2 is the frequency stabilizing tank circuit for all vacuum tubes, and that the filament tuning circuit constitutes in effect regeneration coils, the regeneration being changed by tuning the filament circuit. Feedback is effected through the interelectrode capacity between grid and filament in each tube. An advantage of the arrangement of the invention is that the oscillation generation system will function even though one or more of the vacuum tubes fail to function.

Output energy from the oscillation generation system is derived from loop 14 coupled to the common filament concentric line. Condenser 15 located across the conductors 2, 13 of the filament concentric line serves to tune the filament concentric line to the operating frequency.

The mechanical details of the construction embodying the circuit of Fig. 1 are shown in Figs. 2, 3, 4, 5 and 6. Fig. 2 is a front elevation of the complete mechanical construction of the oscillation generation system, while Fig. 4 is a section of Fig. 2 along line 4-4, showing in detail the construction of the two resonant concentric lines.

Fig. 2 shows clearly the general arrangement of the preferred form of vacuum tubes 4, 4, each of which has two anode prongs A and two grid prongs G. Only two of the four vacuum tubes 4, 4 have been shown in Fig. 2 in order to simplify the drawings and to better show the details of the mechanical construction. The anode and grid prongs have individual clips mounted on

the face or end plate 18 (note Fig. 4) which end plate couples together the inner and outer conductors 1, 2 and 2, 13 (note Fig. 4). The vacuum tubes are mounted on metallic strips 18, 18 arranged around a circle and insulated from each other and from the end plate 18. The metallic strips 18, 18 are insulated for anode direct-current voltage from end plate 18 by thin mica sheets, thus forming radio frequency by-pass condensers to maintain these strips at very low radio frequency potential. Each strip 18 is provided with an indented portion in its center to permit the vacuum tube to be mounted as near to the end plate 18 as possible. Screws 20, 20 located within insulating bushings serve to securely mount the strips 18, 18 upon the end plate. The two anode terminals or prong clips for each vacuum tube are in direct current conductive engagement with the strip 18 accommodating the vacuum tube. The two grid terminals for each vacuum tube are insulated from the strip 18 and from the end plate 18 and are connected together in the interior of the concentric line 1, 2 by means of a sector shaped metallic plate 21 which is folded over in the form of a right angle to constitute the loop 8 coupling the grid to the inner conductor 1 (note Figs. 3 and 4). The direct connection between the grid terminals and the direct connection between the anode terminals for each vacuum tube reduces the lead inductances of grid and anode electrodes to a minimum, and reduces the deleterious effects of the lead impedances. The rear view of plate 21 is shown in Fig. 3 which illustrates how the wide ends of the plate 21 make direct contact with the grid clips. The U-shaped loop 8 is completed by means of a metal plate 22 in direct contact with angle plate 21 but insulated from the end plate 18 by means of a mica spacer 23. Fig. 4 shows in section a side view of grid loop 8 and its associated elements. The grid loop 8, in turn, is connected by a metal strip 24 to a filter can containing therein a choke coil 9 in series with the grid connection 24 (note Figs. 3 and 6). The sleeve or shield of the filter can, labeled 11', is in direct contact at one end with its associated metallic strip 18, and serves as the anode connection for supplying the anode of the vacuum tube with a positive polarizing potential. The sleeve 11' is insulated from the terminals for the choke coil 9 and from the end plate 18 and forms with the end plate a by-pass capacitor (labeled 11 in Fig. 1), thus grounding the anode for radio frequency energy. It should be noted that the anode clips of each vacuum tube are directly mounted upon and are in direct contact with its associated strip 18, while the grid clips on the other hand do not contact strip 18.

The three filament leads for each vacuum tube extend from one end of the tube envelope and are inserted into individual prong clips 25, 25 forming an integral part of the filament metallic tuning loop 12. (Note Fig. 5.) These elements 25, 25 terminate in small metal segments 26, 26 which are insulated from each other and form low impedance by-pass capacitors with each other. The central segment 26 makes contact from a direct current standpoint both with the hollow metallic loop 12 and with that filament lead which extends to the center point of the filament. The outer segments connect with the legs of the filament and with the heater wires 17 which are located in the interior of the hollow loop 12. The three segments 26, 26 form a capacity with a stud 27, which is adjustable by a

screw 28 (note Fig. 4). By adjusting screw 28, I am able to tune the filament leads so as to obtain the proper oscillating voltage. The loop 12 is mounted on a metallic stud 35 which is insulatingly supported from the end plate 19.

For tuning the filament concentric line 2, 13, there is provided a metallic plate 15' in direct contact with cylinder 13 and adjustable by knob 29 to vary the capacity between conductors 2 and 13. The plate 15' is located at a high impedance point on the filament concentric line where it has a maximum effect.

The concentric line 2, 13 extending from end plate 19 to end plate 36 is electrically one-half wavelength long at the operating frequency. It will thus be seen that the capacitor formed by plate 15' is located at a place where the current in the line is low and the impedance is high, while the filament loops 12 are located at places where the current in the line is high, corresponding to a low impedance point.

The inner conductor of concentric line 1, 2 is shown provided with a metallic bellows 31 and an Invar rod 32 for maintaining the overall length of the inner conductor 1 substantially constant with change in temperature. As is known, the Invar rod has a low temperature coefficient of expansion characteristic. A knurled knob 33 and a spring arrangement 34 enables adjustment in length of the inner conductor in either direction. The overall length of the inner conductor 1 including bellows is made to be electrically approximately one-quarter of a wavelength long at the operating frequency.

Fig. 7 is a schematic circuit diagram illustrating a modification of the oscillation generation system of Fig. 1, and differs from Fig. 1 mainly in the provision of individual tuned circuits for the filaments of the vacuum tubes. Instead of the common concentric line 2, 13 employed in Fig. 1 for all of the vacuum tube filaments, there is provided in Fig. 7 separate low loss concentric line resonators for the filaments of the tubes. With this exception, the circuit and mechanical construction of Fig. 7 is substantially identical with that of Fig. 1, and the same parts in both figures are labeled with the same reference numerals.

Each vacuum tube 4 of Fig. 7 has its filament 1 tuned by means of a concentric line comprising an inner tubular conductor 36 and an outer grounded tubular conductor 37, the conductors being directly connected together at the end of the line removed from the filament. Both conductors 36, 37 are tuned by means of a slider 38 which contacts the outer surface of 36 and the inner surface of 37 and is movable over the lengths of these conductors. The heater leads 17 for the legs of the filament 7 extend within the interior of the inner conductor 36 and are capacitively coupled to the inner conductor at the end of the line nearest the filament by means of by-pass condensers 39, 39 and also capacitively coupled to the outer conductor 37 at the end of the concentric line farthest away from the filament by by-pass condensers 40, 40, thus providing paths of low impedance to these conductors for energy of the operating frequency. The connection from the mid point of each filament extends directly to the end of the inner conductor nearest the filament.

Output energy is derived from the oscillation generation system in any suitable fashion, preferably by a connection 41 to one of the filament concentric lines, as shown. In order to couple

the oscillation system to a symmetrically arranged or balanced output circuit, the connection 41 is divided at point 42 into two conductors 43, 44 which differ in length from each other by one-half wavelength, thus providing on conductors 43, 44 currents of equal intensity and opposite phase which are symmetrical with respect to ground.

The constructional arrangement of the circuit of Fig. 7, insofar as it differs from that for Fig. 1, is shown in Figs. 8, 9, 10 and 11. Fig. 8 shows the front elevation view and Fig. 9 the rear elevation view of any quarter of the complete mechanical construction, all quarters being alike. Fig. 10 is a fragmentary side view of one-half of the mechanical construction for Fig. 7. Fig. 11 shows one of the filament concentric lines of Fig. 7 in detail.

An inspection of those figures will show that the individual filament concentric lines are mounted on and around the periphery of cylindrical conductor 2, the outer conductor 37 of each filament concentric line being supported at one end by end plate 19 and at another point in its length by a supporting stud 45. The three filament leads for each filament extending from one end of the vacuum tube are secured at one end of the filament concentric line to individual metallic plates 26', 26' by screws 46. Plates 26', 26' are insulated from each other and, except for the central plate 26', are also insulated from the inner conductor 36. The central plate 26' is directly connected to the end of the inner conductor 36. The outer plates 26', 26' are connected to the legs of the filament and also to the heater wires 17. The effect of the mechanical arrangement of plates 26', 26' is to provide capacitive paths of extremely low impedance to radio frequency energy between the outer plates 26', 26' and the nearest end of the inner conductor 36. At the other end of the filament concentric line the inner and outer conductors 36 and 37 are directly connected together and capacitively coupled to the heater leads 17 to form by-pass condensers, as shown. The movable slider 38 in the interior of the filament concentric line may consist of two pair of metallic sliding spring contacts S, S which are electrically connected to a central disc-like ring R contacting both conductors of the line. One or more screws 47 projecting through slots in the outer conductor, are used to adjust the position of the movable slider.

What is claimed is:

1. An oscillation generation system comprising an electron discharge device having grid and anode electrodes within an envelope, each of said electrodes being provided with a plurality of terminal prongs located externally of said envelope and spaced apart by a distance which is at least one-half the shortest dimension of said envelope, a direct conductive connection between the grid terminal prongs and a direct conductive connection between the anode terminal prongs, said connections having individual clips for said prongs, and a resonator circuit coupled to said connections for controlling the frequency of operation of said generator system.

2. An oscillation generation system comprising an electron discharge device having grid and anode electrodes within an envelope, each of said electrodes being provided with a plurality of terminal prongs located externally of said envelope and spaced apart by a distance which is at least one-half the shortest dimension of said envelope, a direct conductive connection having relatively

large surface area joining the grid terminal prongs externally of the device and a direct conductive connection also having relatively large surface area joining the anode terminal prongs externally of the device, said connections having individual clips for said prongs, and a resonator circuit supporting said direct conductive connections and controlling the frequency of operation of said generator system.

3. An oscillation generator system comprising an electron discharge device having grid and anode electrodes within an envelope, each of said electrodes being provided with a plurality of terminal prongs located externally of said envelope and spaced apart by a distance which is at least one-half of the shortest dimension of said envelope, a filament for said device, a direct conductive connection having relatively large surface area joining the grid terminal prongs externally of the device and a direct conductive connection also having relatively large surface area joining the anode terminal prongs externally of the device, said connections having individual clips for said prongs, tuning means for said filament, and a resonator circuit supporting said direct conductive connections and controlling the frequency of operation of said generator system.

4. An oscillation generator system comprising an electron discharge device having grid and anode electrodes within an envelope, each of said electrodes being provided with a plurality of spaced terminal prongs extending from opposite sides of the envelope, a direct conductive connection between the grid terminal prongs and a direct conductive connection between the anode terminal prongs, said connections having individual clips for said prongs, and a resonator circuit coupled to said connections for controlling the frequency of operation of said generator system.

5. An oscillation generation system comprising a plurality of vacuum tubes, each having anode and grid electrodes within an envelope, each of said electrodes being provided with a plurality of spaced terminal prongs extending from different portions of the associated tube envelope, said prongs being spaced apart by a distance which is at least one-half of the shortest dimension of said envelope, a direct conductive connection between the grid terminal prongs of each tube and a direct conductive connection between the anode terminal prongs of each tube, said connections having individual clips for said

prongs, a single resonator circuit coupled to said grid electrodes of said tubes for controlling the frequency of operation thereof.

6. An oscillation generation system comprising a plurality of vacuum tubes, each having cathode, anode and grid electrodes within an envelope, each of said anode and grid electrodes being provided with a plurality of spaced terminal prongs extending from different portions of the associated tube envelope, said prongs being spaced apart by a distance which is at least one-half of the shortest dimension of said envelope, a direct conductive connection between the grid terminal prongs of each tube and a direct conductive connection between the anode terminal prongs of each tube, said connections having individual clips for said prongs, a single resonator circuit coupled to said grid electrodes of said tubes in electrically parallel relation for controlling the frequency of operation thereof, and tuning means coupled to the cathodes of said vacuum tubes.

7. In combination, an electron discharge device having grid and anode electrodes within an envelope, each of said electrodes being provided with a plurality of spaced terminal prongs located externally of said envelope, said prongs being spaced apart by a distance which is at least one-half of the shortest dimension of said envelope, a direct conductive connection externally of said envelope between said anode terminal prongs, and a direct conductive connection externally of said envelope between said grid terminal prongs, each of said connections having individual clips for said prongs.

8. An oscillation generator system comprising an electron discharge device having grid and anode electrodes within an envelope, each of said electrodes being provided with a plurality of spaced terminal prongs extending from opposite sides of the envelope, a resonator circuit for controlling the frequency of operation of said generator system, and means coupling said resonator circuit to said grid and anode electrodes, said means including individual clips for the plurality of terminal prongs for each electrode, said system being so constructed and arranged that there is a direct conductive connection externally of the envelope of said device between the terminal prongs for each electrode.

HALLAN EUGENE GOLDSTINE.
